INVENTOR.

Thomas A. DeVilbiss,
By Owner, Burn & Crampton,
His Atty.

UNITED STATES PATENT OFFICE.

THOMAS A. DE VILBISS, OF TOLEDO, OHIO, ASSIGNOR TO THE DE VILBISS MANUFACTURING CO., OF TOLEDO, OHIO, A CORPORATION OF OHIO.

ATOMIZER.

Specification of Letters Patent.

Patented Aug. 8, 1916.

1,193,524.

Application filed December 6, 1915. Serial No. 65,434.

To all whom it may concern:

Be it known that I, THOMAS A. DE VILBISS, a citizen of the United States, and a resident of Toledo, in the county of Lucas and State of Ohio, have invented a certain new and useful Atomizer; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to atomizing instruments of the type employed for applying a medicated liquid in spray or finely atomized form to the nose and throat.

The object of my invention is the provision of improved means for attaching a nasal tip to the discharge nozzle of an atomizer, which tip is adapted to have sliding spring engagement with the nozzle carrying parts to yieldingly retain the tip in operative relation to the nozzle and to facilitate an easy and quick placing on or removing of the tip from the nozzle, thus enhancing the practicability and commercial value of instruments of this character.

The invention is fully described in the following specification, and while, in its broader aspect, it is capable of embodiment in numerous forms, a preferred embodiment thereof is illustrated in the accompanying drawings, in which,—

Figures 1 and 2 are top plan and side views of an atomizer embodying the invention, and Fig. 3 is an enlarged view of a portion of the air and liquid discharge tubes of an atomizer and associated nozzle with a nasal tip mounted thereon and in section.

Referring to the drawings, 1, 1 designate the air and liquid discharge tubes of an atomizer, which tubes are disposed side by side and have their outer end portions sprung apart and terminating in inwardly turned portions 2, which form trunnions for fitting into axially aligned openings provided in the opposite sides of a nozzle 3 adjacent to its rear end, as indicated in Fig. 3 and as well understood in the art. It will be understood that the bores of the two tubes 1, 1 open into a common discharge orifice in the nozzle 3.

The atomizer tubes 1, 1 are made of spring

metal and have their outer sides tapering slightly outward for a short distance rearwardly from their forward ends so that the distance between the outer sides of the tubes is the greatest a short distance back from 60 the nozzle, as best indicated in Fig. 3. It is preferable, but not necessary, to tie the tubes together in closely disposed relation intermediate their ends, as by a band 4, so that the outer sides of the tubes taper in 65 opposite directions to the point of the nozzle.

The nasal tip 5 is of elongated shell form, being preferably formed from sheet metal, and has its forward end closed except for 70 a central opening 6 provided therein and of suitable size for the discharge end of the nozzle 3 to project through. The tip 5 is preferably tapered or gradually enlarged in diameter for a distance rearward from 75 its forward end and then slightly contracted in gradually tapering form to slightly restrict the rear open end of the tip. The tip 5 is of suitable length to cause its rear restricted end to extend slightly beyond the 80 point of maximum width of the two tubes 1, 1 when the tip is placed over the nozzle and the outer ends of the tubes, with the nozzle projecting through the tip opening 6. The tip is circular in cross-section and the 85 diameter of the rear end opening thereof is slightly less in length than the distance between the more remotely spaced outer side portions of the tubes, thereby causing the tip when forced rearward into operative position over the tubes to effect a slight inward springing of the tubes, the normal outwardly sprung position of which is indicated by the dotted lines 7 in Fig. 3.

It is evident that the co-operative spring 95 engagement of the tubes 1 and rear end of the tip 5 in the manner described quite firmly holds the tip in position on the tubes and at the same time facilitates an easy and quick placing on or removal of the same 100 from the tubes. It is also evident that the projecting of the nozzle 3 through the restricted opening 6 in the forward end of the tip effects a centering of the forward end of the tip with respect to the nozzle and 105 serves to prevent any transverse twisting or displacing movements of the tip with respect to the nozzle and tubes.

I wish it understood that my invention is not limited to any specific construction, 110

arrangement or form of the parts, as it is capable of different modifications without departing from the spirit of the claims.

Having thus described my invention, what I claim as new and desire to secure by Letters Patent, is—

1. In an atomizer, a nozzle, air and liquid discharge tubes carrying said nozzle and projecting rearwardly therefrom in transversely spaced relation, said tubes having the distance between their outer sides broadened with respect to their forward ends at a point which is distant from said ends, and a nasal tip for removably receiving the nozzle and forward end portions of said tubes, said tip being of a length for its rear end to extend beyond the broadened portion of said tubes and having its rear end opening of a size less than the distance between the broadened outer side portions of the tubes to effect an inward springing of the tubes when the tip is placed in operative engagement therewith.
2. In an atomizer, a nozzle, air and liquid tubes carrying said nozzle and extending rearward therefrom, said tubes having their forward ends spaced apart and outwardly bulged at a point to the rear of the nozzle,

and a nasal tip for fitting over said nozzle and the forward end portions of said tubes and having its forward end provided with a restricted opening for receiving and cooperating with the nozzle to center the tip with respect thereto and having its rear end adapted to coact with the bulged portion of said tubes to yieldingly retain the tip in position thereon.

3. In an atomizer, a nozzle, air and liquid tubes projecting rearwardly in spaced relation from opposite sides of said nozzle and having their outer sides tapered outward for a distance from their forward ends, and a nasal tip for fitting over said nozzle and the outwardly tapered end portion of said tubes, said tip having a restricted opening in its forward end for receiving and coacting with the nozzle to center the tip therewith and having its rear end slightly contracted and coacting with said tubes at a distance from their forward ends to effect an inward springing of the tubes when the tip is placed thereon.

In testimony whereof I have hereunto signed my name to this specification.

THOMAS A. DE VILBISS.
